[57] CLAIM

The ornamental design for a mason's trowel, as shown and described.

DESCRIPTION

FIG. 1 is top, front and right side perspective view of a mason's trowel showing my new design;

FIG. 2 is a top, rear and right side perspective view thereof;

FIG. 3 is a reduced front elevational view thereof;

FIG. 4 is a reduced right side elevational view thereof;

FIG. 5 is a reduced top plan view thereof;

FIG. 6 is a reduced rear elevational view thereof;

FIG. 7 is a reduced bottom plan view thereof;

FIG. 8 is a top, rear and right side perspective view of a second embodiment of the mason's trowel, the areas not shown being identical to the first embodiment; and,

FIG. 9 is a reduced top, front and right side perspective view of the mason's trowel with the spacer and brick wall shown in broken lines for illustrative purposes only and forming no part of the design;
